CLAIM

The ornamental design for a boiler for a combustion plant having a pressurized fluidized bed, as shown.

DESCRIPTION

FIG. 1 is a top perspective view of the boiler for a combustion plant having a pressurized fluidized bed; and,

FIG. 2 is a bottom perspective view of the boiler for a combustion plant having a pressurized fluidized bed, in inverted condition showing the three sides opposite to those shown in FIG. 1.

FIG. 1

FIG. 2
